Howson & Howson

UNITED STATES PATENT OFFICE.

WILLIAM E. WRIGHT, OF PHILADELPHIA, PENNSYLVANIA, ASSIGNOR TO ACME CAN COMPANY, OF PHILADELPHIA, PENNSYLVANIA, A CORPORATION OF PENNSYLVANIA.

ICE-CREAM FREEZER.

Application filed October 1, 1925. Serial No. 59,958.

This invention relates primarily to the outer bucket and the top cross-bar of ice cream freezers which are made chiefly from sheet metal.

5 The primary object of the invention is to provide an improved means for hinging and latching the cross-bar on the bucket in order to provide greater strength and rigidity.

In the accompanying drawing, I have 10 shown the embodiment of the invention which I now deem preferable but it will be understood that the drawing is for illustrative purposes only and that changes may be made in the construction within the scope 15 of the appended claims without departing from the spirit of the invention.

Of the drawings:

Fig. 1 is a plan view of an ice cream 20 freezer bucket and cross-bar embodying the invention.

Fig. 2 is a fragmentary vertical sectional view taken along the line 2-2 of Fig. 1.

Fig. 3 is a vertical sectional view through 25 the cross-bar, this view being taken along the line 3-3 of Fig. 1 and also showing the hinge construction between the cross-bar and the bucket.

Referring to the drawing, 1 represents the 30 bucket which is circular in horizontal section and which has an outward projecting beaded top edge 2. The cross bar is represented at 3, this being preferably formed of sheet metal and being provided with depending side flanges 4, 4. The wall of the 35 bucket is provided with two apertures or slots 5, 5 closely adjacent the bead. The cross bar is provided with hinge portions 6, 6 which fit around or engage the bead 2 and which enter the said slots 5, 5.

40 Preferably and in accordance with one feature of the invention, a short portion 7 of the bead 2 is made straight preferably by being bent inward. The straight portion 7 is long enough to provide a bearing for the hinge members 6, 6 it being clear that a more satisfactory bearing for the said members is provided by the straight portion than would be provided if the initial curvature had been allowed to remain.

45 The bead 2 is also provided with a second straight portion 8 which is diametrically opposite the straight portion 7, this straight portion 8 being formed by bending the bead inward as is clearly shown in Fig. 2. The

cross-bar 3 is provided with a spring latch 55 portion 9 which is adapted to fit over the straight portion 8 of the bead and to engage the outer side thereof.

Preferably in order to more firmly hold or lock the free end of the cross-bar to the 60 bucket, I provide the flanges 4, 4 with longitudinally extending projections 10 at the lower outer corners thereof. These projections 10 are adapted to be forced downward and under the inward bent straight portion 65 8 of the bead as clearly shown in Fig. 2.

It will be clear that the projections 10 in co-operation with the spring latch portion 9, will serve to firmly hold the cross-bar not only against vertical movement, but 70 also against horizontal or lateral movement with respect to the bucket.

I claim:-

1. In an ice cream freezer, the combination of a sheet metal bucket which is circular 75 in horizontal section and which has an outward projecting beaded top edge, the said bucket having two hinge slots at one side and the said bead being straight for a short distance adjacent the said slots and for a 80 short distance diametrically opposite the said slots, and a cross-bar provided with hinge portions at one end engaging the first said straight portion of the bead and entering the said slots, the said cross-bar having 85 a spring latch portion at the other end adapted to engage the other straight portion of the bead.

2. In an ice cream freezer, the combination of a sheet metal bucket which is circular 90 in horizontal section and which has an outward projecting beaded top edge, the said bucket having two hinge slots at one side and the said bead being bent inward for a 95 short distance diametrically opposite the said slots, and a cross-bar provided with hinge portions at one end engaging the bead and entering the said slots, the said cross-bar having depending side flanges with longitudinally projecting lower corners adapted to be forced under the inward bent portion of the bead.

3. In an ice cream freezer, the combination of a sheet metal bucket which is circular 105 in horizontal section and which has an outward projecting beaded top edge, the said bucket having two hinge slots at one side and the said bead being bent inward for a

short distance diametrically opposite the said slots, and a cross-bar provided with hinge portions at one end engaging the head and entering the said slots, the said cross-bar having depending side flanges with longitudinally projecting lower corners adapted to be forced under the inward bent portion of the head and also having a spring latch portion adapted to engage the outer side of the said inward bent portion of the head.

4. In an ice cream freezer, the combination of a sheet metal bucket which is circular in horizontal section and which has an outward projecting beaded top edge, the said bucket having two hinge slots at one side

and said bead being bent inward to form a short straight portion adjacent the said slots and being also bent inward to form a short straight portion diametrically opposite the 20 said slots, and a cross-bar provided with hinge portions at one end engaging the first said straight portion of the bead and entering the said slots, the said cross-bar having depending side flanges with longitudinally 25 projecting lower corners adapted to be forced under the inner side of the second said straight portion of the bead and also having a spring latch portion adapted to engage the outer side of the second said 30 straight portion.

WILLIAM E. WRIGHT.
